UNITED STATES PATENT OFFICE.

JOHN ERNEST GEORGE GEISEL, OF WEISSPORT, PENNSYLVANIA.

SLEIGH ATTACHMENT FOR VEHICLES.

SPECIFICATION forming part of Letters Patent No. 627,995, dated July 4, 1899.

Application filed April 4, 1899. Serial No. 711,748. (No model.)

To all whom it may concern:

Be it known that I, JOHN ERNEST GEORGE GEISEL, a citizen of the United States, residing at Weissport, in the county of Carbon and 5 State of Pennsylvania, have invented certain new and useful Improvements in Bob-Sleigh Attachments for Vehicles; and I do hereby declare the following to be a full, clear, and exact description of the invention, such as will 10 enable others skilled in the art to which it appertains to make and use the same.

This invention relates to bob-sleigh attachments for vehicles and is in the nature of an improvement upon the construction described 15 and illustrated in Letters Patent No. 621,242, granted to me March 14, 1899.

One object of the present invention is to provide a better form of rest for the vehicle-axle where it bears upon the bob-sleigh.

Another object is to provide more convenient means for applying the eyes to the axle.

Another object is to provide more convenient and reliable means for locking the lever or crank-shaft to the bob-sleigh.

25 A further object of the invention is to provide means whereby the projecting spindle of the axle may be gotten rid of and protected while the bob-sleigh attachments are applied to a vehicle and also to provide means for 30 thrusting the spindle into operative position when required in use.

Other objects and advantages of the invention will appear in the course of the subjoined description.

35 The invention consists in a bob-sleigh attachment for vehicles embodying certain novel features and details of construction and arrangement of parts, as hereinafter fully described, illustrated in the drawings, and incorporated in the claims.

In the accompanying drawings, Figure 1 is a side elevation of the bob-sleigh, also illustrating in full and dotted lines the manner of applying the same to a vehicle-axle. Fig. 2

45 is a detail perspective view of the upper portion of the bob-sleigh, showing the rock-shaft, the operating lever or crank therefor, and the means for locking said lever or crank. Fig. 3 is an enlarged detail plan view of the lever 50 or crank locking device. Fig. 4 is a cross-section through a hollow vehicle-axle, showing the manner of applying the spring seat

and clip thereto. Figs. 5 and 6 are detail perspective views of the parts of the clip and seat shown in Fig. 4. Fig. 7 is a detail view of 55 one of the hooks applied to the rock-shaft. Fig. 8 is a longitudinal section through the hollow axle, showing a double-ended reversible spindle and the spring for thrusting the spindle outward, also showing the means for 60 locking the spindle in place. Fig. 9 is a similar view showing the spindle entirely inclosed and concealed within the axle. Fig. 10 is a detail perspective view of the clip which carries the eye. Fig. 11 is a side elevation of 65 another form of adjustable spindle. Fig. 12 is a detail longitudinal section through the end of the hollow axle, showing a plain cap fitted thereon. Fig. 13 is a similar view taken through the axle having a wooden cap-piece. 70 Fig. 14 is a detail perspective view of the cap shown in Fig. 13.

Similar numerals of reference designate corresponding parts in all the figures of the drawings.

75 Referring to the drawings, 1 designates a bob-sleigh consisting of a pair of runners 2, raves or braces 3, and upper horizontal or top bars 4, connected by means of the cross-beam 5, on the opposite ends of which are mounted 80 supports or rests 6, extending transversely of the beam 5 and adapted to receive and support the vehicle-axle, as shown in Fig. 1, the upper edges of said supports being reinforced by metal wear-plates 7, secured thereto by 85 suitable fasteners 8. Extending through the rests or supports 6 is a rock-shaft 9, which may be either round, as shown in Figs. 1 and 2, or square, as in Fig. 7. Bearing-sleeves 10 pass through the supports 6, in which the 90 rock-shaft 9 is journaled. The shaft is provided at two points with hooks 11, secured at the proper places on the shaft by means of set-screws 12. One end of the shaft 9 is square; as shown at 13, to receive the operating crank or lever 14. The lever 14 is provided near its upper end with a rectangularly-projecting arm 15, which is designed to pass through an eye or loop 16 in the end of the bar 4, and is provided with a recess 17, 100 comprising spaced shoulders 18, between which is received a stout flat spring 19, one end of which is secured, by suitable fasteners 20, to the bar 4, as clearly shown in Fig. 3.

After the rock-shaft has been turned the arm 15 is thrust through the eye 16 and the spring 19 automatically snaps into engagement with the notch 17, thus locking the crank or lever 14 in position and preventing it from becoming accidentally displaced and lost.

Connected to the axle at proper intervals are clips 21, made in two parts, the lower part 22 fitting beneath the axle and the upper part 23 above the axle, the part 23 forming a rest on which the elliptical springs of the vehicle bear. The half-round recesses 24 in which the axle is received are preferably serrated to secure a firmer engagement between the 15 clip and axle, and the lower part 22 is also provided with an upwardly-projecting stud 25, which enters a hole in the axle, thereby preventing any possibility of the clip turning on the axle. The lower part 22 is provided 20 with ears 26 for the passage of the terminals of suitable bolts for connecting the two parts of the clip. It is also provided with an inward extension 27, having on its bottom a depending eye or loop 28, designed to be engaged by the hooks 11 on the rock-shaft 9 for connecting the bob-sleigh to the axle in the manner explained in my former patent hereinabove referred to. The part 27 is also provided with oppositely-located ears 29, de- 30 signed to receive a clip or U-shaped bolt passing over the axle. The clips or bolts 30 clamp the vehicle-springs upon the part 23. If desired, the bolts 30 may be simply straight bolts, as shown in Fig. 4, passing through the 35 ears 26 at their lower ends and at their upper ends through cross-bars resting upon and passing over the saddle or part 23.

The axle (indicated at 31) is tubular or hollow, and in connection therewith I provide a 40 spindle 32, having each end tapered, as at 33, to form a journal for the vehicle-wheel. This spindle may be reversed or turned end for end and either end thereof used. The spindle 32 is adapted to slide longitudinally within the 45 shaft 31 and is normally pressed or urged outward by means of a coil-spring 34, arranged within the central portion of the axle and provided at its opposite ends with buttons 35, which bear directly against both spindles at 50 opposite ends of the hollow axle. The spindle is also provided at suitable intervals with recesses or sockets 36 for receiving the ends of set-screws 37, as shown in Figs. 8 and 9, whereby the spindle is held in its adjusted position either for use as an ordinary vehicle- 55 axle or when thrust inward for enabling the vehicle to be used upon bob-sleighs, thus doing away with any projections beyond the ends of the hollow axles of the vehicle. In 60 this manner the spindles are prevented from injuring persons or property near by and are at the same time protected and prevented from being injured or broken in case of the 65 sleigh overturning or striking against a fence or other obstruction. The sockets 36 are so located with relation to the spindle 32 that when the spindle is thrust outward for use

both screws 37 may be used to secure the spindle rigidly in place. When the spindle is thrust inward, the inner screw 37 engages with 70 the recess or socket 36 nearest the outer end of the spindle, as shown in Fig. 9.

Each end of the axle is exteriorly threaded to receive a cap or nut 38, and this cap or nut has applied to its outer face a washer 39, being held constantly in place by means of screws or other fasteners 40 to prevent wear on the nut or cap. When the washer becomes worn, it may be detached from the nut or cap and substituted by a new one, thus obviating the 80 necessity for providing a new cap or nut. On the outer end of the spindle is a nut 41, which is provided upon its inner face with a washer 42, secured by means of screws or fasteners 43. When the spindle is thrust inward into the 85 axle, as shown in Fig. 9, the nut 41 is reversed, the outer reduced end 44 thereof fitting within the bore of the axle, as shown in Fig. 9.

In Fig. 10 I have shown a slight modification in the form of the clip which carries the eye or loop for receiving the hooks on the rock-shaft where clips are needed on axles in connection with which elliptical springs are not employed. In Fig. 11 I have shown a spindle 45, only one end of which is tapered, but which is adapted to slide inward within the axle similar to that 32 hereinabove described. If desired, the spindle may be entirely removed from the axle and a plain cap or nut 46 placed thereon, as shown in Fig. 12. Where the axle 100 is provided with a wooden cap-piece 47, the nut or cap is provided with a corresponding enlargement 48 at one side, as shown in Figs. 13 and 14, said enlargement being adapted to be brought into alignment with the cap-piece 47.

From the foregoing description it will be seen that I have made a number of improvements upon my former patent referred to which will not only facilitate the application 110 of the bob-sleighs to a vehicle and the removal of the same therefrom, but which will also enable the axles to be more readily equipped or provided with the eyes 28 and also do away with the projecting ends of the spindles after 115 the sleighs have been removed therefrom. The application of the bob-sleigh to the vehicle-axle is exactly the same as described in my former patent, the initial step in the operation of applying the bob-sleigh being shown 120 in full lines in Fig. 1 and the final position of the parts being illustrated in dotted lines in the same figure.

It will of course be understood that the features of construction hereinabove described 125 are susceptible of changes in the form, proportion, and minor details, which may accordingly be resorted to without departing from the principle or sacrificing any of the advantages of the invention.

Having thus described the invention, what is claimed as new, and desired to be secured by Letters Patent, is—

1. A bob-sleigh attachment for vehicles,

having a rock-shaft with axle-engaging means thereon, in combination with an operating-lever detachably connected to said rock-shaft and having a laterally-extending arm, and a 5 spring-lock for engaging said arm.

2. A bob-sleigh comprising a rock-shaft and axle-engaging means, in combination with an operating-lever detachably connected thereto and having a laterally-extending arm provided with a notch, and a spring adapted to snap into engagement with said notch for the purpose specified.

3. A bob-sleigh comprising a rock-shaft equipped with axle-engaging means, in combination with an operating-lever detachably connected thereto and having a laterally-extending arm, spaced shoulders on said arm, and a spring connected to the bob-sleigh and adapted to snap into engagement with said 20 arm and lie between the shoulders thereon, substantially as described.

4. A bob-sleigh having a rock-shaft with axle-engaging means, in combination with an operating-lever detachably connected thereto, a laterally-extending arm near the other end of said lever, an eye on the frame of the 25 sleigh through which said arm passes, and a spring-lock connected to the frame of the sleigh and adapted to snap into engagement 30 with said arm, substantially as described.

5. The combination with a bob-sleigh having a rock-shaft provided with axle-engaging means, and means for operating said rock-shaft, of a sectional or divided clip adapted 35 to be removably fitted upon the vehicle-axle

at an intermediate point and provided with a depending eye, substantially as and for the purpose specified.

6. The combination with a hollow axle, of a spindle fitted to slide therein, and a spring 40 within the axle behind the spindle for normally urging the spindle outward into operative position, substantially as described.

7. The combination with a hollow axle, of a spindle slidably fitted in the end thereof, 45 means for normally urging the spindle outward, so as to project beyond the axle, and a set-screw for holding the spindle within the axle, substantially as described.

8. The combination with a hollow axle made 50 tubular in form from end to end, of a double-ended spindle adjustable within the axle and having both ends made tapering, and a set-screw penetrating the axle and engaging the spindle for holding it at the desired adjustment.

9. The combination with a hollow axle, of spindles slidably fitted in the opposite ends thereof, and a spring interposed between and pressing against the inner ends of the two 60 spindles and serving to normally urge said spindles outward and away from each other, substantially as described.

In testimony whereof I affix my signature in presence of two witnesses.

JOHN ERNEST GEORGE GEISEL.
